ARTHUR C. WATSON, OF MARIETTA, OHIO

METHOD OF AND APPARATUS FOR ADVERTISING

Application filed October 17, 1929. Serial No. 400,282.

This invention relates to the art of advertising and is directed to a method as well as advertising apparatus which will have a high value from the standpoint of 5 attractiveness and which will hold the attention of observers, so that such attention may be directed to advertising matter forming a part of the apparatus.

More especially the purpose of this invention is to provide a new and effective 10 means of visual stimulation which shall have a high degree of efficiency because of its novelty, variety and beauty, in addition to area, movement, change, and because of its 15 particular adaptability to the problem of focusing attention agreeably upon desired advertising or similar matters.

Briefly stated the method of this invention consists in rotating, at a rate of speed satisfying the "critical frequency" for continuity 20 of sensation, in a circular, cylindrical or conical path, one or more luminous gaseous tubes, preferably such as contain neon, and preferably of the conventional elongated 25 tubular form, so mounted that a substantial part, at least, of the tube is in its long axis approximately normal to the direction of movement. The three factors thus involved, viz., shape of light source, character 30 of illuminant and method of presentation will now be more fully described.

With regard to the shape of the source of light, the ordinary gas tube, especially in simple straight shape, is peculiarly suitable 35 for the purpose of this invention, because of its elongated or linear form. A lamp of spherical or non-linear form, if moved rapidly across the field of vision, must form a streak or zone of luminosity, whereas the linear form, if moved in a 40 direction approximately normal of its length, generates an extended area much greater, relative to its actual size, than that of a lamp of non-linear form. This linear form of illuminant does not necessarily depend upon the linear form of lamp, but, if such a source of illumination were contained 45 in a non-tubular shaped lamp, it would, because the line of least resistance for the passage of the current tends to be the shortest

distance between electrodes, still partake essentially of the linear shape. Variations of pressure or other conditions may tend to divert the luminous path from exact rectilinearity, but the luminous path nevertheless tends to maintain the linear form, and hence serve the same purpose as is secured by the truly tubular form. 55

The invention is therefore not limited to the use of straight linear tube lamps, exclusively, for curved tubular lamps, especially when used in conjunction with straight tubes, are useful, and generate a more brilliant area in proportion to the degree to which they generate a smaller area 60 than a similar length of straight tube would secure. Neither is this invention limited to the positioning of the tube normal to the direction of movement, but requires only that a substantial part of each tube be so 65 placed. Departures of parts of the tubes from positions at right angles to the line of translation produce variations of intensity or pattern that serve to enhance the 70 beauty or novelty of the optical impression. 75

In practically carrying out this invention, I may employ one or more low pressure gaseous luminous tubes of the type commonly known as Crookes's tubes. These tubes embody certain marked characteristics among 80 which may be mentioned: their susceptibility to variation in appearance due to differences in pressure of gas within the tube; their susceptibility to variations in character 85 of luminescence due to differences in frequency and wave form of the energizing electrical current, which variations in luminescence produce variations in appearance when said light is moved across the field of 90 vision at a relatively rapid rate; their commonly elongated, linear form or shape of luminous area; their colorlessness or invisibility when not luminous. These tubes, when employed in connection with this invention, are particularly productive of an 95 exceedingly wide variety of novel visual effects because of the almost innumerable combinations of different conditions of pressure and electrical energization which are readily obtainable. 100

The appearance of tubes of the character described varies considerably in accordance with differences in pressure. These differences in appearance are, more particularly, 5 differences in striation and differences in general contour.

The character of gaseous tube lights is such that there are observable nodes or rings, relatively close together, of greater 10 brightness, separated by regions of less brightness. In the ordinary conventional tube this is not always observable, because the glow is so intense as to produce on the eye the impression of a continuous bar or 15 stream of light. However, when such tubes are moved more or less rapidly, because of the persistence of vision, there results the appearance of a spread out area of illumination and this luminous area has a very 20 peculiar or unique appearance in that the nodes or rings referred to above are visible as small more or less mottled areas of light and dark color, and are, furthermore, arranged in a "staggered" or zigzag pattern. 25 The whole effect is of the "herringbone" type of pattern, and is of an entirely unique and peculiarly attractive appearance. These nodes or rings of greater brilliance are known in physics as *striæ*, and, may 30 be most simply defined as layers of luminosity separated by dark spaces. The number and size of these *striæ*, and the size of the relatively dark spaces between them, vary with differences in pressure of the gas 35 within the tube. At relatively low pressures, the dark intervals are relatively larger, whereas at somewhat higher pressures they are so small as to produce, at least in the stationary tube, the visual impression of a continuous body of light. 40

A further characteristic of the luminous low pressure gas tube is that the *striæ* appear constantly to be in a state of oscillation or local perturbation. Upon rapid 45 translation of the tube, however, these oscillating *striæ* appear as a minutely mottled extended area (in cases where the current is of intermittent impulses of appreciable duration, as for example in the ordinary 60 cycle A. C. current). Because the apparent small local motions of the *striæ* are in reality stroboscopic effects due to exceedingly rapid discharges of energy succeeding each other in slightly different positions, the visual 50 effect of the light, when the tube is rapidly moved, is that of relatively stationary mottlings arranged in a sort of staggered or step-like pattern.

Moreover, in high pressure tubes (for example 60 tubes wherein there is a pressure substantially equivalent to atmospheric pressure) the discharge occurs not at all or with difficulty; as pressure is decreased, the luminosity occurs at first as a bundle of wavy 65 threads of light, having a somewhat mobile

appearance, (known in the industry as "wormy" tubes). At still lower pressure the luminosity becomes more solid and stable in appearance. This is known as the "positive column". At still lower pressures, 70 the striation, referred to above, becomes more and more obvious. Hence it may be stated that the character of the gaseous tube light is such that under certain conditions of gas pressure, the luminous area takes on 75 the appearance of a wavy ribbon, or "wormy" streak of light. When moved or rotated, as contemplated in this invention, this wavy or "wormy" motion, because of the persistence of vision and the resulting 80 spread of the luminous area, produces very striking and peculiar patterns of light, giving the whole area a kind of palpitating or throbbing appearance. Such tubes may also thus be used in carrying out this 85 invention.

Other characteristics of the luminous gaseous tube light which are of importance in the purpose of this invention, consists in the differences in visual effect which are 90 obtainable by means of variations in the frequency and the wave form of electric current which is used to cause the gases to glow. This is of particular importance in the case of neon gas tubes, because of the 95 peculiar nature of the gas, by virtue of which it glows and ceases to glow with substantial instantaneity. Such variations in the current have little or no effect upon the visual appearance of the light, so long 100 as it remains in a stationary position. When rotated or moved as in the method of this invention, these electrical differences are responsible for important differences in visual effect. It is characteristic of tubes of this 105 type that the light source is intermittent, and with the peculiar capacity of neon gas to come to the maximum brightness of incandescence and likewise to cease to glow with substantial instantaneity, the result of 110 this intermittent operation is to produce clearly marked intervals of luminous and non-luminous condition. This characteristic, however, is, according to this invention, coupled with appropriate movement of the 115 light source to produce the pattern of alternate luminous and non-luminous areas. The width of these areas is dependent upon the rate of the current frequency, in relation to the rate of rotation of the tube. 120

The durations of the luminous and non-luminous periods may be varied by appropriate control of the electrical current supplied to the tube, so that the relative extent of luminous and non-luminous areas is likewise varied. When a plurality of lamps are combined, different ratios of luminous to non-luminous periods may be employed in different lamps, producing, for instance, a widespread luminous field within which 130

there appears relatively small areas of definite outline, of a different intensity or a different color, such for example as red stars on a striped field of blue.

- 5 The frequency of the intermittent illumination may also be varied, and combinations of different frequencies (all predetermined) may be had, so that, for instance, the red stars on the striped field of blue, may have 70
10 the appearance of the stars moving more or less slowly in one direction while the striped blue field moves in the opposite direction.

A further characteristic of the type of illuminant herein before discussed and which is of importance for the purpose of this invention resides in the fact that when in non-luminous condition the gas is invisible. When rotated or otherwise moved by energizing the gas by electric current for a certain interval, and then discontinuing the current for a certain interval, the area of the path traversed by the tube or tubes is by turns luminous and invisible, or practically invisible except for the small amount of light that may be reflected from the surface of the glass tubes themselves. This characteristic of the illuminant is highly useful in such a device as an advertising 80
25 apparatus for instance, wherein it is desirable to attract attention by means of novel or beautiful color effects and then to place in the area thus attentively observed a message, trade name, etc. According to this 85
30 invention, this is very simply and effectively achieved by the method of alternately energizing and deenergizing the rotating gas tubes.

With reference to the mode of presentation to the eye, this method has both spatial and temporal aspects. Stated generally it is accomplished by rotation, at a predetermined rate sustained through repetitive cycles, in a circular, conical or cylindrical path, at a speed conformable to the demands of the "critical frequency" for continuous sensation, and in a direction substantially normal to the longitudinal axis of the lamp.

45 50 It is important to note that this rotation or movement, when combined with the two other factors, produces visual effects substantially different from the similar movement of an ordinary light, or from other forms of movement of a similar light.

These effects have numerous novel characteristics of considerable importance. For instance, in the stationary condition, the visual effect is of a continuous line or ribbon of light, continuous both in time and space, whereas upon rotation the fact of actual intermittency of the light and its peculiar instantaneous on-set and shut-off, (entirely obscured in the stationary condition) because of the persistence of vision, is

revealed as a unique spatial pattern of alternating luminous and non-luminous bands, bars, or triangles forming in the aggregate a disk, zone, or cylinder of luminous color. This is a unique effect, produced only by 75
80 this unique combination of these three factors, form of lamp, character of illuminant, and method of presentation to the eye. The "herringbone" pattern is also the product of this combination of these three factors.

It should also be noted that movement of the character defined, when a plurality of lights having different frequencies, or different luminous periods, or both are used has the peculiar virtue of bringing out, in the form of novel visual effects, contrasts in the actual distribution of energy which are entirely lacking in stationary position because of the temporal continuity of the sensation resulting from continuous pulses of illumination. For instance, at appropriate intensities, a lamp activated by an ordinary 60 cycle current and one activated by a high frequency current of substantially instantaneous impulses, will have in the stationary state an identical appearance. If, however, these lamps be given the movement to which I have referred, their illuminations 90
95 will be strikingly dissimilar in appearance, more specifically the resultant spatial patterns will be different in number of discrete parts or elements, the size and shape of these parts, and the brilliance of these parts.

Furthermore, the effect of the said movement upon the mixture of colors, when lamps of different colors are combined, is different from that of similar movement of other types of light. For instance when a red and a blue tube are combined instead of producing a purple, by retinal blending, as in the case of ordinary lights, rotation in this case produces, not a common pervasive purple, but alternate bands or stripes of red, blue and purple; red appearing at 100
105 a point corresponding to the non-luminous period of the blue, blue in the non-luminous period of the red, and purple at the point of retinal overlappings of the luminous periods of both.

110 Features of the invention, other than those specified, will be apparent from the herein-after detailed description and claims, when read in conjunction with the accompanying drawings.

115 The accompanying drawings illustrate different practical embodiments of the invention, but the constructions therein shown are to be understood as illustrative, only, and not as defining the limits of the invention.

120 Figure 1 is a diagrammatic perspective view showing apparatus embodying the present invention.

125 Figure 2 is also a perspective view showing a modified form of the invention.

In practically carrying out the invention, as shown in the accompanying drawings, one or more neon tubes are mounted to rotate about an axis with reference to which the tube or tubes are segmentally disposed. 5 The tubes are adapted to be electrically energized to cause their illumination and current may be fed to the tubes in different ways within the invention. Furthermore, the advertising feature of the invention may partake of various forms. 10

However, for the purpose of concrete illustration, attention is first directed to Figure 1, wherein I have shown two neon tubes designated 1 and 2. These tubes are mounted firmly upon a suitable carrier 3 which may be of any appropriate structure, but for illustrative purposes is shown as a circular glass plate. The tubes are firmly secured 15 to the plate by suitable attaching devices 4, so as to be relatively immovable with respect to the plate. The plate is mounted fixedly upon a shaft 5 adapted to be driven from a suitable prime mover through appropriate operative connections, such for 20 example as the pulley 6 fixed on the shaft and driven through the belt 7 from the prime mover 8 illustrated as an electric motor.

30 Current is fed to the tubes from one or more suitable sources of current supply and for the purpose of illustration the feed of this current is as follows. Fixed to the shaft 5 or to the back of the disk 3 at the center thereof is a sleeve 9 of insulating material, whereby the sleeve is caused to rotate with the carrier 3. Upon this sleeve is mounted a plurality of collector rings 10, 11, 12 and 13. The collector ring 10 is connected to 35 one terminal of the tube 1 through an appropriate electrical connection 14. The other terminal of said tube is connected through a suitable electrical connection 15 to the adjacent end of the tube 2, while the 40 opposite end of the tube 2 is provided with a suitable electrical connection 16 which leads to the collector ring 11. Wiping contacts 17 and 18, respectively, engage with the rings 10 and 11 and these two wiping 45 contacts are connected to a suitable source of current supply which may be conveniently 50 an alternating current transformer.

With this arrangement current is fed from the transformer through the tubes 1 and 2 55 in series and serves to energize the tubes as they are rotated from the motor 8. The tubes may in practice be of any appropriate shape as stated and they may be of the same or different characteristics. Very attractive 60 color effects have been produced by using an ordinary red neon tube as the tube 1 and by using as the tube 2 a neon and mercury tube which gives a blue light, so that 65 as the tubes are rotated with the carrier, very beautiful effects due to blending of the

red and the blue colors are obtained. I do not restrict the present invention, however, in this connection as I may use any suitable neon tubes of the same or different colorings or of the same or different characteristics without departing from this invention and it is moreover within the invention to use a single neon tube mounted to rotate as stated. 70

In addition to the tubes 1 and 2, I have 75 shown in Figure 1, additional tubes 19 and 20 mounted on the carrier plate 3 which latter tubes are of ornamental shapes. These tubes may be energized from the collector rings 10 and 11, so as to operate at the same 80 frequency and from the same source of power as the tubes 1 and 2. Very beautiful effects, however, are produced if the tubes 19 and 20 are subjected to substantially instantaneous operation. When employing 85 ordinary commercial current and passing it to the tubes 1 and 2 through a transformer as shown, the periods of individual energization of the tubes 1 and 2 are of appreciable duration, and as the tubes are rapidly rotated about the axis of the shaft 5, there 90 results illumination which produces the optical sensation of a circular zone or disk of light of a brilliancy less, however, than the brilliancy of the individual tubes when 95 viewed at rest. If, however, tubes are operated so that their illumination, i. e., the flashes resulting from illumination at predetermined frequencies are substantially instantaneous, the marked increase in brilliancy will result as compared to the illumination of the tubes 1 and 2 as specified. 100

It is for this reason that in practice I prefer, without limiting the invention thereto, to utilize one or more additional sources of light 19 and 20 and to energize them in a manner that such sources will result in substantially instantaneous flashes of illumination. As shown, this may be accomplished by connecting the tubes 19 and 20 by a suitable electrical connection 21, while one terminal of the tube 19 is electrically connected by a connection 22 with the collector ring 12 and the other terminal of the tube 20 has an electrical connection 23 with the collector 110 ring 13.

With the collector rings 12 and 13 are associated wiper contacts 24 and 25 connected with a suitable source of substantially instantaneous electrical energy. This energy 120 may be supplied in various ways but can conveniently be obtained through an induction coil with a suitable interrupter or vibrator. Direct current may be fed to the induction coil from a battery or other source. 125

When the arrangement as described is in operation, the tubes 1 and 2 will produce the optical effect of a circular zone or disk of light of relatively low intensity as compared to relatively bright flashes resulting 130

from the instantaneous energization of the tubes 19 and 20 operating at an appreciably higher frequency. In the particular arrangement shown the optical effect has been obtained of brilliant light flashes upon a background of colored light of less intensity. This effect, however, is merely illustrative of the invention and the invention is obviously not confined thereto.

10 The advertising matter whereby particular business establishments may be advertised may partake of various forms. Very satisfactory results however have been obtained by the arrangement shown in Figure 15 1, wherein there is positioned back of the carrier 3 an advertising card 26 embodying the words "John Doe Shoes." Any appropriate advertising may of course be embodied in this card which when placed directly back of the carrier 3 is visible through the carrier while the carrier is rapidly rotating and with all of the tubes deenergized. It will of course be understood that as the carrier 3 is transparent and the tubes are 25 transparent the rotation of these parts at high speed will render them practically invisible and a person standing in front of the apparatus can see directly through the carrier and tubes and read the advertising matter on the card 26. In practice it is found desirable to rotate the carrier at appropriate speed with the tubes energized for a period and then discontinue the energization of the tubes for a period so that persons viewing 30 the light phenomenon will suddenly be confronted with the advertising matter and then after a relatively short period renewing the energizing of the tubes. Thus by alternately energizing and deenergizing the tubes 35 through successive periods, the device becomes attractive to persons while the tubes are energized, the advertising function being carried out during intermediate periods when the tubes are deenergized. Appropriate timing mechanism is preferably associated with the sources of current supply so as to control the periods of illumination and non-illumination. This timing mechanism may be of any conventional form and it has 40 not been thought necessary to illustrate it in the accompanying drawings. It may be controlled directly from a shaft 5 or from any suitable clockwork or other timed controlled mechanism.

45 55 It will of course be understood that the illumination of the tubes and their speed of rotation may be such that when energized they will form a color screen through which the advertising matter may be read. On the other hand, it has been found highly practical to so operate the device that the advertising matter will be wholly obscure when the tubes are illuminated and exposed to view only when the tubes are deenergized.

60 65 In Figure 2, I have shown a somewhat

different disposition of the parts while maintaining the same function as in the preceding figure. Thus in Fig. 2, the carrier 3a is shown as cylindrical and for example in the form of a glass tube mounted to rotate on suitable axial trunnions 5a to which power is delivered through a belt and pulley connection 7a—6a from a suitable prime mover. The trunnions 5a are illustrated as hollow and through these trunnions extends a fixed 70 supporting rod 27 which serves to support within the carrier a stationary advertising card 26a. Any suitable number of tubes 1a, and 2a are mounted on the carrier either interiorly or exteriorly thereof as may be desired and they are energized through appropriate electrical connections, such for example as collector rings (not shown) mounted upon the trunnions 5a in the same general manner as shown in Fig. 1.

75 80 85 The primary difference between the structure of Figures 1 and 2 is that the tubes traverse a cylindrical path instead of traveling in substantially a plane as in Fig. 1. These two arrangements are illustrated in the drawings in order to show different embodiments of which the invention is susceptible, but I wish it understood that the invention is not limited to details of construction but resides rather in the combination of elements.

90 95 100 In practically carrying out the invention, the various neon tubes may vary in size and shape, but in every instance shown, it will be noted that each tubes occupies a segmental relation to the axis about which it rotates.

105 110 115 Thus by reference to Figure 1, it will be noted that the tube 1 is contained within the segment 28, the tube 2 is contained within the segment 29 and the tubes 19 and 20 are contained within their corresponding segments 30. By reference to Figure 2, it will be similarly noted that the tube 1a is contained within the segment 28a and that the tube 2a is similarly positioned. When the tubes are thus segmentally disposed with reference to their axis of rotation, rotation of such tubes produces highly desirable and ornate colored lighting effects having a high degree of attractive value in the advertising art. It will be further noted that when the tubes are thus disposed, an appreciable portion of their length is substantially normal to the direction of their movement and they thus generate a relatively large area of brilliance.

120 125 130 The tubes 1a and 2a are shown as straight in each instance while the tubes 19 and 20 are shown as of ornamental configuration. This is for illustrative purposes and I do not restrict the present invention in this regard. Tubes of widely different characteristics may be used without departing from the invention and actual experience has dem-

onstrated that neon tubes referred to in the trade as producing "worm" light effects and which are generally considered undesirable for stationary advertising signs, will produce unusually pleasing effects when utilized in connection with this invention.

The foregoing detailed description sets forth the invention in its preferred practical form. It will be noted that the invention 10 embodies numerous features of novelty, some of which may be employed without necessarily employing all and furthermore certain of these features may be duplicated to give more extensive or a series of combination illuminating effects. For these reasons the invention is to be understood as fully commensurate with the appended claims.

Having thus fully described the invention, what I claim as new and desire to secure 20 by Letters Patent is:

1. In an advertising apparatus, the combination of a source of relatively low frequency neon light, a source of substantially instantaneous neon light, means for mounting both of said sources of neon light for rotation about a predetermined axis, means for rotating said sources of neon light about said axis, and means for independently energizing each of said sources of neon light 25 while they are rotating.

2. In an advertising apparatus, the combination of a plurality of neon tubes, means for mounting said tubes for rotation about a common axis, means for energizing one of 30 said tubes in a substantially instantaneous manner to cause substantially instantaneous flashes of light to emanate from said tube, means for energizing another of said tubes with current impulses of appreciable duration to cause light flashes of appreciable duration to emanate from the latter tube, and means for rotating said tubes about said axis.

3. In an advertising apparatus, the combination of a plurality of neon tubes, means for mounting said tubes for rotation about a common axis, each of said tubes being segmentally arranged with respect to the axis about which they are mounted to rotate, means for energizing one of said tubes in a 45 substantially instantaneous manner to cause substantially instantaneous flashes of light to emanate from said tube, means for energizing another of said tubes with current 50 impulses of appreciable duration to cause light flashes of appreciable duration to emanate from the latter tube, and means for rotating said tubes about said axis.

4. In an advertising apparatus, the combination of a plurality of Crookes tubes, means for mounting said tubes for rotation about a common axis, means for energizing one of said tubes in a substantially instantaneous manner to cause substantially instantaneous flashes of light to emanate from 60

said tube, means for energizing another of said tubes with current impulses of appreciable duration to cause light flashes of appreciable duration to emanate from the latter tube, and means for rotating said tubes about said axis.

5. In an advertising apparatus, the combination of a plurality of Crookes tubes means for mounting said tubes for rotation about a common axis, each of said tubes being segmentally arranged with respect to the axis about which they are mounted to rotate, means for energizing one of said tubes in a substantially instantaneous manner to cause substantially instantaneous flashes of light to emanate from said tube, means for energizing another of said tubes with current impulses of appreciable duration to cause light flashes of appreciable duration to emanate from the latter tube, and means 70 for rotating said tubes about said axis.

6. In an advertising apparatus, the combination of a source of relatively low frequency neon light, a source of relatively high frequency neon light, means for mounting both of said sources of neon light for rotation about a predetermined axis, means for rotating said sources of neon light about said axis, and means for independently energizing each of said sources of neon light 80 while they are rotating.

7. The method which consists in simultaneously rotating a plurality of Crookes tubes across a zone of vision, and energizing the different tubes by electrical currents of 90 respectively different frequencies.

8. The method which consists in rotating a plurality of Crookes tubes about a common axis, energizing one of said tubes by an electric current of relatively low frequency and energizing another of said tubes by current of relatively high frequencies, while said tubes are being rotated.

9. In an advertising apparatus, the combination of a plurality of neon tubes of 110 different gas pressures, means for supporting said tubes for rotation about a predetermined axis, means for thus rotating said tubes, and means for electrically energizing said tubes while they are rotating.

10. In an advertising apparatus, the combination of a plurality of neon tubes of different gas pressures, means for supporting said tubes for rotation about a predetermined axis, means for thus rotating said 120 tubes, and means for electrically energizing each tube at a predetermined substantially constant frequency while it is rotating.

11. In an advertising apparatus the combination of a suitable advertising matter 125 arranged to be observed from a predetermined direction, a plurality of neon tubes of different gas pressures mounted to rotate on a predetermined axis and during such rotation to intercept the field of observa- 130

tion, means for rotating said tubes, and means for periodically electrically energizing each of said tubes, whereby a zone or disk of illumination will be interposed between the observer and the advertising matter when the tubes are energized.

12. In an advertising apparatus, the combination of a plurality of Crookes tubes, of different gas pressures, means for supporting said tubes for rotation about a predetermined axis with substantial portions of the tube disposed approximately at right angles to the paths of travel of the tubes, means for thus rotating the tubes, and means for electrically energizing the tubes while they are rotating.

13. In an advertising apparatus, the combination of suitable advertising matter arranged to be observed from a predetermined direction, a plurality of Crookes tubes of different gas pressures mounted to rotate on a predetermined common axis with an appreciable portion of each tube disposed approximately at right angles to its path of movement to intercept the field of observation, means for rotating said tubes, and means for periodically electrically energizing the tubes, whereby a zone or disk of illumination will be interposed between the observer and the advertising matter when the tube is energized.

14. The method which consists in simultaneously rotating a plurality of Crookes tubes of different gas pressures in space with appreciable portions of said tubes substantially normal to the path of their movement in space, and electrically energizing said tubes while they are rotating to cause the tubes to generate an illuminated zone.

15. The method which consists in rotating a plurality of Crookes tubes of different gas pressures in space with an appreciable portion of the length of each tube disposed substantially normal to its direction of rotation, and intermittently energizing each of said tubes, as it is thus rotated, by an electrical current of sufficiently low intensity to permit optical manifestation of the alternate periods of illumination and non-illumination of each tube to be visibly apparent.

16. The method which consists in rotating a plurality of Crookes tubes of different gas pressures and different colors across the same field of vision, and electrically energizing said tubes while they are thus rotated.

Signed by me at Marietta, Ohio, this 15th day of October, 1929.

ARTHUR C. WATSON.
